UNITED STATES PATENT OFFICE.

FRANK J. MATCHETTE, OF MILWAUKEE, WISCONSIN.

DUST-COLLECTOR.

No. 926,070.

Specification of Letters Patent.

Patented June 22, 1909.

Continuation of application Serial No. 235,936, filed December 8, 1904. This application filed January 2, 1907. Serial No. 350,434.

To all whom it may concern:

Be it known that I, FRANK J. MATCHETTE, a citizen of the United States, residing at Milwaukee, in the county of Milwaukee and 5 State of Wisconsin, have invented certain new and useful Improvements in Dust-Collectors, of which the following is a specification, reference being had to the accompanying drawing, forming a part thereof.

10 The main objects of this invention are to separate and remove dust and dirt from air with which they are taken up or mingled, and generally to improve the construction and operation of devices of this class.

15 It consists in certain novel features of construction and in the peculiar arrangement and combinations of parts as hereinafter particularly described and defined in the claims.

In the accompanying drawing like characters designate the same parts in the several figures.

Figure 1 is a central vertical section on the line 1 1, Fig. 2, of a dust collector embodying the invention; Fig. 2 is a cross section on the 25 line 2 2, Fig. 1; Fig. 3 is an enlarged longitudinal section of the ejector; Fig. 4 is a perspective view of the removable closure for the dust receptacles in the lower part of the device; Fig. 5 is an enlarged view partly in 30 plan and partly in horizontal section on the line 5 5, Fig. 6, of the closure and associated parts of the dust collector; Fig. 6 is a view of the same partly in side elevation and partly in section on the line 6 6, Fig. 5; Fig. 7 is a 35 front elevation on an enlarged scale of one of the fastenings for securing the removable internal parts of the device in the main or outer casing; Fig. 8 is a vertical section of the same and of associated parts on the line 8 8, Fig. 2; Fig. 9 is a perspective view of the eccentric 40 bolt forming a part of each fastening; Figs. 10, 11, 12 and 13 are detail views in perspective of parts for spreading and supporting the strainer bag; and Fig. 14 is an enlarged 45 view partly in section and partly in side elevation showing the strainer spreading and supporting devices assembled in connection with associated parts of the dust collector.

The apparatus herein shown and described 50 for the purpose of illustration is intended and designed more particularly for use in connection with portable cleaning implements, to

be connected therewith by hose or flexible pipes for taking up and removing dust and dirt from floors, carpets, furniture and the like, and is provided with an ejector for exhausting air therefrom and producing an air current through the same and through the cleaning implements, but with little or no change in the essential parts of the apparatus 60 it may be adapted to strain and purify air for ventilation and other purposes, and the air current for operating the same may be produced by pressure as well as by suction.

Referring to the accompanying drawing 65 the apparatus comprises a main or outer casing 1, open at the bottom and closed at the top, an inner shell or casing 2, having conical or tapering heads, and a discharge opening at the lower end, a conical or tapering shell 3, 70 surrounding the lower head of the shell 2 and forming therewith an annular dust receptacle, and a strainer 4 inclosing the inner shell 2 above the annular dust receptacle into which it opens at its lower end.

75 The casing 1, shell 2 and strainer 4 are preferably of cylindrical shape and when the parts are assembled are arranged coaxially with relation to each other. The main or outer casing 1 and the inner shell 2 may be 80 conveniently made of metal, and the strainer 4 is preferably made of cloth.

An inlet pipe 5 secured in a central opening in the upper end of the casing 1, projects 85 downwardly a short distance into the same. The upper head of the inner shell 2 is centrally perforated and attached to a flanged sleeve 6, which is removably fitted upon the end of the inlet pipe 5 projecting into the upper part of the casing 1. To the lower end 90 of the sleeve 6 is attached a spiral pipe 7 which opens tangentially at its lower end into the upper part of the dust separating chamber 8 inclosed by the shell 2. A number of air outlet pipes 9, lead upwardly from near the axis of the chamber 8 through the upper head of the shell 2.

The cloth strainer bag 4 is supported at its upper end and spread and stretched taut by a resilient expandible frame composed of a 100 central collar 10, spring wire arms 11, radiating from said collar, and arcuate cross pieces 12 secured to the outer ends of the arms 11 and forming a broken contractible ring. The

ends of the cross pieces 12 are bent inwardly and downwardly as shown at the left in Fig. 12, or are connected by tubes 13, as shown at the right, to avoid wrinkles in the strainer bag and prevent puncturing the same. Each of the tubes 13 is fixed to one of the cross pieces which it connects and slides freely upon the other. The cloth around the opening in the upper end of the strainer 10 through which the sleeve 6 passes, is reinforced by a sheet metal eyelet 14, folded over it, as shown in Figs. 11 and 14, a cord or wire being preferably folded in the cloth around the opening to prevent the cloth from 15 being pulled out of the eyelet. The collar 10 with the eyelet or ring 14 above it, is clamped on the sleeve 6, as shown in Fig. 14, between a shoulder on the sleeve and a nut 15 threaded on its upper end.

20 The strainer supporting and stretching frame tends by reason of the resiliency of the arms 11 and cross pieces 12, to assume and maintain the form in which it is shown in Fig. 12, so that when the strainer bag 4 is drawn 25 over it and fastened at the lower end as hereinafter explained, it will be spread and held taut by said frame, as shown in Figs. 1 and 14.

The casing 1 is provided on the inside some distance above its lower end with a ring 16, 30 as shown in Figs. 1 and 8, having an inwardly projecting horizontal flange, and to the upper edge of the conical shell or dust receptacle 3, is attached a ring 17 having an outwardly projecting horizontal flange corresponding 35 with the flange on the ring 16. The ring 17 is also formed or provided with an upwardly projecting rim or extension 18, which terminates at its upper edge in an outturned flange or bead. The open lower end of the strainer 40 bag 4 is attached to this rim or extension by a cord or wire, preferably a split ring of spring wire just below the outturned bead.

The shell 2 is provided on the outside adjacent to its lower tapering head with a ring 45 19 formed at intervals with radial lugs or wings which bear against the rim 18 and thus hold said shell central with relation to the casing 1 and strainer 4.

The truncated head at the lower end of the 50 shell 2 and the truncated conical shell 3, are attached at their lower edges to a circular frame comprising two parallel obliquely flanged rings 20 and 21, which are connected on opposite sides as shown in Figs. 5 and 6, 55 by posts or uprights 22 and 23. Within the rings of this frame is fitted a cylindrical closure 24, formed at its lower end with an outturned flange which with the lower ring 21 and an interposed gasket or packing ring, 60 as shown in Fig. 1, forms an air tight joint. The closure is provided at its upper end on opposite sides, as shown in Fig. 4, with outwardly projecting lugs 25, and the posts 23 are formed as shown in Figs. 5 and 6 with 65 vertical grooves 26 to permit the insertion of

the closure and the passage of said lugs above the inner edge of the upper ring 20, which slopes upwardly, as shown in Fig. 6, from the posts 23 toward the posts 22, so that when the closure is turned after being inserted 70 in the frame, the flange at its lower end will be drawn up by said lugs tightly against the packing ring between it and the ring 21. The posts 22 and 23 are preferably made triangular in section, as shown in Fig. 5, to prevent dust and dirt from lodging behind them. The upper end of the closure 24 fitting into the ring 20, stops the opening in the lower end of the chamber 8 and effectively cuts off 80 communication between said chamber and the strainer chamber surrounding it through the dust receptacle 3. In the recess on its under side the closure is formed with a central cross web which stiffens and strengthens it and serves as a handle for inserting and removing it from the frame in which it is fitted.

85 To avoid the noise caused by the air escaping from the dust collector, the outlet 27 from the strainer chamber is connected with a muffler comprising a perforated pipe 28 90 coiled in the form of a volute around the conical shell or dust receptacle 3 and closed at its lower end. This pipe is inclosed by a conical or tapering case 29, which is attached as shown in Figs. 1 and 6, at its lower edge 95 with the lower edge of the shell 3 to the ring 21. The space outside the muffler pipe between the shell 3 and the case 29 is filled with porous or fibrous material such as cotton, and the inclosing case 29 and the lower 100 part of the casing 21 are perforated as shown in Fig. 1, to permit the escape of air discharged from the muffler.

105 It will be observed that the internal parts of the apparatus thus far described, comprising the shell 2, the shell or dust receptacle 3, the strainer 4 and the muffler, are connected with each other and are removable together bodily from the main or outer casing 1. To secure and hold these internal 110 parts in place in the casing it is provided on opposite sides as shown in Figs. 2, 7, 8 a: d 9, with fastenings 30. Each of these fastenings consists of a bolt 31, fitted to turn and slide 115 in a barrel 32, which is attached to the casing 1. The bolt is formed at its inner end with an eccentric or cam 33, and at or near its outer end is provided with a radial pin or handle 34, which works in an angular slot in the barrel 32, a part of this slot being parallel 120 with the axis of the barrel to permit endwise movement of the bolt, and a part transverse to said axis to permit rotary movement of the bolt. When the bolts are thrust inwardly and their eccentrics 33 are turned upwardly against the outwardly projecting flange of the ring 17, as shown in Fig. 8, said flange is forced and held tightly against the gasket or packing ring interposed between 125 it and the inwardly projecting flange of the 130

ring 16, thereby forming an air tight joint. The shell or dust receptacle 3 with the flanged ring 17 thus constitutes a removable closure for the opening in the lower part of the outer casing 1, and affords means for removing any dust which may work through the strainer 4 and in time accumulate in the space between said casing and the strainer.

As thus far described the apparatus is 10 equally well adapted for operation by forcing air into it through the inlet pipe 5, as well as by exhausting the air therefrom through the outlet 27. An ejector 35 is shown for exhausting air from the apparatus. This 15 ejector, as shown in detail in Fig. 3, has a compressed air supply connection 36, a jet nozzle 37, a combining tube 38, and a valve 39 controlling the admission of compressed air to the jet tube. The vacuum chamber 20 40 of the ejector is connected by a lateral branch and coupling 41 with the outlet 27 of the dust collector, and the discharge pipe 42 of the ejector is connected by a coupling 43 and an elbow 44 with the upper end of the 25 muffler pipe 28. A ring 45 of metal or heavy material, is attached to the strainer 4 as shown in Fig. 1, to dislodge the dust which adheres to the inner surface of the strainer, the apparatus being jarred or shaken so as to 30 cause the ring to strike against the casing 1, or inner shell 2, and thus jar the strainer.

The apparatus operates as follows: The injector being connected with a source of compressed air and a cleaning implement or 35 other source of dust laden air being connected with the inlet pipe 5, when the ejector valve 39 is opened, air is exhausted from the dust collector through its outlet 27 in the casing 1, and discharged into the muffler, 40 from which it escapes without noise through the holes in the pipe 28, thence through the porous or fibrous material surrounding said pipe and out through the holes in the inclosing case 29 into the lower part of the main 45 casing, from which it escapes through the openings therein around its base. Air being exhausted from the strainer chamber between the casing 1 and shell 2, induces a 50 current of dust laden air through the inlet pipe 5 and the spiral pipe 7 into the chamber 8, the pipe 7 imparting a vortical or whirling movement to the air current in said chamber whereby the particles of dust and dirt are thrown outwardly by centrifugal force 55 against the shell 2 and are caused to settle in the lower part of said chamber, while the air, freed from a large part of the dust and dirt entrained therewith, flows upwardly in the center of the chamber and escapes there- 60 from through the pipes 9 into the upper part of the strainer 4. As the air passes outwardly through the strainer, the remaining dust carried thereby is caught by the strainer and falling therefrom collects in the dust receptacle 3 at its base. The greater part of

the dirt and dust having been separated from the air in the chamber 8, a much larger volume of air will pass through the strainer than would otherwise be possible, and the area of the strainer as well as the size of the 70 apparatus, may be correspondingly reduced. The air freed from dust passing out through the ejector into the muffler pipe 28, issues therefrom in numerous jets into which it is divided, its velocity being materially reduced, so that its escape from the muffler will be practically noiseless. Should there be any dust left in the air after it passes through the strainer, as will sometimes happen when the apparatus is first started, it 75 will be caught and held by the porous or fibrous material enveloping the muffler pipe. By lifting and dropping the apparatus or moving it quickly sidewise so as to cause the ring 45 to strike against the inclosing 80 casing 1, or against the shell 2, dust adhering to the inside of the strainer will be removed therefrom and the meshes of the strainer will be kept clear. By removing the closure 85 24 from time to time, the dust and dirt collecting in the annular receptacle 3 and the lower end of the chamber 8, will be simultaneously discharged therefrom. The internal parts of the apparatus are readily removed for inspection and repairs, or for the 90 renewal of the strainer cloth, by turning and withdrawing the bolts 31 as indicated by dotted lines in Figs. 7 and 8, so as to release the flanged ring 17 with which they normally engage. The strainer is easily and 95 quickly detached from the sleeve 6 and from the rim 18 by unscrewing the nut 15 and removing the cord or wire surrounding the rim 18.

Various changes in the details of construction and arrangement of parts may be made within the scope of the following claims without departing from the invention.

This application is a substitution for and continuation of application Ser. No. 235,936, filed December 8, 1904.

I claim:

1. In a dust collector, the combination of a closed upright chamber of substantially cylindrical form, having an air and dust inlet at the upper end, a separate air outlet leading out of the central part of the chamber, an opening for the removal of dust at the lower end and a closure for said opening, means connected with the inlet for imparting to the air entering said chamber a spiral movement around its walls, a dust receptacle surrounding the base of said chamber, and a strainer surrounding the upper part of said chamber and opening at its lower end 115 into said receptacle, substantially as described.

2. In a dust collector the combination of a closed upright chamber having an inlet and a separate outlet near the upper end 120

thereof, a strainer surrounding said chamber, a dust receptacle communicating with the interior of said strainer at its lower end, and an imperforate casing inclosing said strainer and having an outlet above said dust receptacle, substantially as described.

3. In a dust collector the combination of a closed chamber having an inlet at the upper end and an outlet opening upwardly near the axis of said chamber, a pipe connected with said inlet and having a tangentially directed discharge into said chamber, a strainer surrounding said chamber in communication with the outlet therefrom and means for causing a current of air to pass successively through said chamber and strainer, substantially as described.

4. In a dust collector the combination of a closed chamber having an inlet at the upper end and an outlet leading upwardly from near the axis of the chamber, a pipe connected with the inlet and having a tangentially directed discharge into said chamber, a strainer surrounding said chamber, an annular dust receptacle in communication with the interior of said strainer at its lower end and means for producing a current of air successively through said chamber and strainer, substantially as described.

5. In a dust collector the combination of a chamber having an air inlet at the upper end, an outlet leading upwardly from near its axis and a dust discharge opening at the lower end, a pipe connected with said inlet and having a tangentially directed discharge into said chamber, a strainer surrounding said chamber, an annular dust receptacle communicating with the interior of said strainer at its lower end and having a dust discharge opening at its lower end and a removable closure for said dust discharge openings, substantially as described.

6. A dust collector comprising an inner dust separating chamber, a chamber surrounding said inner chamber and containing a strainer, a dust receptacle at the bottom of the strainer chamber, a muffler surrounding said dust receptacle, a connection between the strainer chamber and muffler and means for producing a current of air successively through the inner chamber, the strainer chamber and the muffler, substantially as described.

7. A dust collector comprising a casing closed at its upper end and open at its lower end and having an inlet at its upper end and an outlet, and internal parts comprising a dust separating chamber having an outlet opening into said casing and provided with means for closing said casing adjacent to its lower end and with an inlet at its upper end adapted to form a closed connection with the inlet of said casing when said internal parts are in place, substantially as described.

8. A dust collector comprising a casing closed at its upper end and open at its lower end and having a tubular inlet at its upper end and an outlet, and internal parts comprising a dust separating chamber having a dust discharge opening at its lower end, a tubular inlet adapted to telescope with the inlet of said casing, an outlet opening into said casing and a removable closure for said discharge opening, substantially as described.

9. A dust collector comprising a casing closed at its upper end and open at its lower end and having an outlet and at its upper end a tubular inlet, and removable internal parts comprising a dust separating chamber having an outlet and a tubular inlet adapted to telescope with the inlet of said casing and a strainer connected with and surrounding said chamber between the outlet therefrom and the outlet in said casing, substantially as described.

10. A dust collector comprising a casing closed at its upper end and open at its lower end and having an outlet and at its upper end a tubular inlet, and removable internal parts comprising a dust separating chamber having an outlet and a tubular inlet adapted to telescope with the inlet of said casing, a strainer connected with and surrounding said chamber between the outlet therefrom and the outlet in said casing, substantially as described.

11. A dust collector comprising a casing closed at the upper end and open at the lower end and having an outlet and at its upper end an inlet connection, and removable internal parts comprising a dust separating chamber having an outlet, a dust discharge opening at the lower end and at the upper end an inlet adapted to form a closed connection with the inlet of said casing, a strainer connected with and surrounding said chamber between the outlet therefrom and the outlet in said casing, an annular dust receptacle surrounding the lower part of said chamber in communication with the interior of said strainer and having a dust discharge opening at its lower end, and a removable closure for stopping both of said dust discharge openings, substantially as described.

12. In a dust collector, the combination of an imperforate casing having an air outlet, a closed chamber within said casing, having a dust discharge opening at its lower end and an air outlet near its upper end, an air inlet connection leading into the upper part of said chamber, said air inlet connection and outlet being constructed and arranged to cause separation within said chamber of

- dirt and dust from the inflowing air, a strainer surrounding said inner chamber within said casing, a dust receptacle located below and communicating with the interior of the strainer and having a dust discharge opening, means for closing said dust discharge openings, and means for producing a current of air through said chamber and strainer, substantially as described.
13. In a dust collector the combination of a strainer bag and means for holding its closed ends distended comprising a number of radial spring arms and arcuate cross pieces attached to the outer ends of said arms, substantially as described.
14. In a dust collector the combination of a strainer bag and means for holding its closed end distended comprising a number of radial spring arms, arcuate cross pieces attached to the outer ends of said arms and tubes connecting adjacent ends of said cross pieces, substantially as described.
15. In a dust collector the combination of a dust separating chamber having a dust receptacle at its base, a tubular inlet connection at the upper end and an outlet, a strainer bag surrounding said chamber over its outlet and having an opening in its upper end through which said tubular inlet passes, means for forming a dust tight connection between said bag and tubular inlet and a frame mounted on said tubular inlet and having resilient arms for distending the upper closed end of said bag, substantially as described.
16. In a dust collector the combination of a dust separating chamber having a dust receptacle at its base, a tubular inlet connection at its upper end and an outlet, a frame mounted on said tubular inlet above said chamber and having resilient arms, a strainer bag drawn over and distended by said frame around the outlet from said chamber and having an eyelet in its upper closed end fitting on said tubular inlet and a nut threaded on said tubular inlet for securing said frame and eyelet together thereon, substantially as described.
17. In a dust collector the combination of dust receptacles arranged one within the other and having concentric openings, a frame attached to said receptacles around said openings and having side openings in communication with the outer receptacle and a single removable closure fitted in said frame and adapted to stop the openings in both receptacles, substantially as described.
18. In a dust collector, the combination of an imperforate casing having an air outlet, a closed chamber within said casing having an inlet and a separate outlet for air, and a dust discharge opening in the lower part thereof, a strainer surrounding said chamber between its air outlet and the air outlet from
- the casing, a dust receptacle located below and communicating with the interior of the strainer and having a dust discharge opening in the lower part thereof, and a removable closure for both of said dust discharge openings and for shutting off communication between the lower part of said chamber and the interior of the strainer, substantially as described.
19. In a dust collector the combination of a closed casing provided with a tubular inlet at its upper end, a dust separating chamber inclosed in said casing and having a tubular inlet, which connects with the inlet through the casing and terminates within said chamber in a tangential discharge, and an outlet leading from the upper central part of said chamber, an annular dust receptacle surrounding the lower end of said chamber and having an opening at its lower end, a removable closure for said opening, a strainer surrounding the upper part of said chamber and the outlet therefrom and attached at its lower end to said dust receptacle and a closure between said dust receptacle and the inclosing casing adjacent to the lower end of the strainer, substantially as described.
20. In a dust collector the combination of a casing provided with a tubular inlet at its upper end, a dust separating chamber inclosed in said casing and having a tubular inlet which connects with the inlet through the casing and terminates within said chamber tangentially thereto and an outlet leading from the upper central part of said chamber, an annular dust receptacle surrounding the lower end of said chamber and having an opening at its lower end, a removable closure for said opening, a strainer surrounding the upper part of said chamber and the outlet therefrom and attached at its lower end to said dust receptacle, a closure between said casing and dust receptacle adjacent to the lower end of the strainer, a muffler surrounding said dust receptacle and a connection between the muffler and the interior of the casing outside of the strainer, substantially as described.
21. In combination a dust separator having a dust receptacle at its lower end, and an air inlet and outlet, a muffler comprising a perforated spiral pipe surrounding said dust receptacle, a perforated case inclosing said pipe and porous material between said pipe and case, and a connection between the air outlet of the dust separator and said pipe, substantially as described.
22. In combination a dust separator, means for producing a current of air through said separator and a muffler comprising a perforated spiral pipe closed at one end and connected at the other end with the air outlet of the separator and the exhaust of the air current producing means, a perforated

case inclosing said pipe and porous material between said pipe and case, substantially as described.

23. In combination a dust separator having an air inlet and outlet, means for producing a current of air through said separator, and a muffler connected with the air outlet of said separator and comprising a perforated pipe surrounding said separator, a per-

forated case inclosing said pipe, and porous material between said pipe and case, substantially as described.

In witness whereof I hereto affix my signature in presence of two witnesses.

FRANK J. MATCHETTE.
